UNITED STATES PATENT OFFICE.

AMOS G. FITZ, OF AUBURN, MAINE, ASSIGNOR TO FITZ-EMPIRE DOUBLE PIVOT LAST COMPANY, OF AUBURN, MAINE, A CORPORATION OF MAINE.

LAST.

1,016,986.

Specification of Letters Patent. Patented Feb. 13, 1912.

Application filed March 9, 1911. Serial No. 613,463.

To all whom it may concern:

Be it known that I, Amos G. Fitz, a citizen of the United States, residing at Auburn, in the county of Androscoggin and State of Maine, have invented certain new and useful Improvements in Lasts, of which the following is a specification.

One of the modern requirements in the art of shoe making is that the lasts above 10 the bottom shall taper upwardly so that the top above the center line is very narrow. This is so to such an extent that the construction shown in my Patent No. 784,149, dated March 7, 1905, weakens the top of 15 the fore part so that in the process of manufacturing shoes and in the wear and tear of factory use the top of the fore part is liable to be broken off. In my said patent, I provided for the necessary upward and 20 forward movement of the heel part relative to the fore part by removing a portion of the sides of the top of the fore part and forming a recess in the heel part to give entrance thereto. A considerable amount of 25 upward and forward movement of the heel part relative to the fore part is absolutely necessary in lasts which are connected by links as distinguished from lasts which are bonded by the ordinary hinge.

30 My present invention is designed to provide a last which shall permit the requisite amount of upward and forward movement without removing any portion of the top at the sides of the fore part, except so much 35 as is necessary to satisfy the requirement before referred to.

In the drawings I have illustrated my improvement and in said drawings Figure 1 is a side elevation of the last embodying my 40 improvement; Fig. 2 is a side elevation partly in section showing the bonding link and resistance spring; and Fig. 3 is a rear end view of the fore part of the last.

Same reference characters indicate like 45 parts in the several figures.

In said drawing A is the heel part and B the fore part of a last, said parts being adapted to be bonded together by one or more links C pivotally mounted in the heel 50 part and fore part respectively and spanning the line of division between the two parts of the last. D is a coil spring set in

the fore part of the last in the path of a prong E on the end of one of the bonding links. The last throughout the fore and heel part at a point spaced apart from the wide bottom part is contracted, as seen at F, Figs. 1 and 3. I claim no invention in thus reducing the top of the last, it being merely demanded by a change in the custom of manufacturing shoes. To permit the heel part to move upwardly and forwardly sufficient to permit easy insertion and removal of the last from the shoe, I divide the last on lines of cut which form on the rear end of the fore part a reëntrant angle G at the top and two salient angles H and I below and on the heel part a salient angle J at the top and a reëntrant angle K below and a gap L extending downwardly into the last from the top. It will be noted that when the last is thus divided and the parts placed end to end the lower salient angle on the end of the fore part fits into the reëntrant angle K in the end of the heel part, 75 thus affording a firm support for the parts of the last when in extended position. When now the heel part is moved upwardly and forwardly it assumes relative to the fore part the position shown in dotted lines in 80 Fig. 1, wherein the salient angle in the heel part fits into reëntrant angle in the fore part, thus affording a very much greater forward movement of the heel part than would otherwise be attainable.

Having thus described my invention and its use, I claim:

A last divided by lines of cut which form on the rear end of the fore part a reëntrant angle at the top and two salient angles below and on the front end of the heel part a salient angle at the top and a reëntrant angle below, and, when the last is in extended position, a gap extending downwardly into it from the top, whereby when the heel of the last is moved upwardly and forwardly the salient angle at the top of the heel part moves forwardly into the reëntrant angle in the fore part and into locking engagement with the fore part.

AMOS G. FITZ.
